DESIGN FOR A MERCHANTISE DISPLAY STAND

Simon Malkin, New York, N. Y., assignor to United Cigar-Whelan Stores Corporation, a corporation of Delaware

Application December 19, 1945, Serial No. 124,862

Term of patent 14 years

(Cl. D80—9)

To all whom it may concern:

Be it known that I, Simon Malkin, a citizen of the United States and a resident of the city of New York, in the county of New York and State of New York, have invented a new, original, and ornamental Design for a Merchandise Display Stand, of which the following is a specification, reference being had to the accompanying drawing, constituting a part thereof, in which

Fig. 1 is a perspective view of a merchandise display stand showing my new design;

Fig. 2 is an edge view;

Fig. 3 is a front elevational view of the same.

I claim:

The ornamental design for a merchandise display stand, as shown.

SIMON MALKIN.
